UNITED STATES PATENT OFFICE

CHARLES A. HAGUE, OF NEW YORK, N. Y.

AIR-PUMP.

No. 899,971.

Specification of Letters Patent.

Patented Sept. 29, 1908

Application filed March 28, 1908. Serial No. 423,836.

To all whom it may concern:

Be it known that I, CHARLES A. HAGUE, a citizen of the United States, and a resident of the city of New York, borough of Manhattan, in the county and State of New York, have invented a new and Improved Air-Pump, of which the following is a full, clear, and exact description.

This invention relates to certain improvements in air pumps, and more particularly to a type of pump especially designed for use with steam-condensing apparatus for all types of steam engines, although the pump may be employed for any purpose where a very high vacuum is desired.

My invention involves connections between the opposite ends of a double-acting pump and the upper and lower portions of a steam condenser or other vacuum chamber, whereby upon one stroke of the piston, air or other gas is withdrawn from the upper portion of the chamber, and upon the return stroke, water or other liquid is withdrawn from the lower portion of the condenser, the pump being so constructed that water is injected into the air end of the pump to insure the complete expulsion of the air and seal the piston.

My invention also involves means whereby the piston may serve to transfer a portion of the liquid from the liquid end of the pump to the air end of the pump during the suction stroke of the latter, to perform this sealing action.

Reference is to be had to the accompanying drawings, forming a part of this specification, in which similar characters of reference indicate corresponding parts in all the figures, and in which

Figure 1 is a side elevation of a turbine showing one form of my improved pump, connected for operation by the turbine and serving to create a vacuum in the condenser of the turbine; Fig. 2 is a vertical section through a slightly modified form of pump; and Fig. 3 is a top plan view of the pump shown in Fig. 2.

My improved air pump may be used in combination with any suitable form of pump, the former serving to remove the air from the condenser, and the latter serving to withdraw the water from the pump, although the special form of pump illustrated is adapted for serving both purposes, that is, withdrawing the air and also withdrawing the water. The pump may be used with a sur-

face condenser, a jet condenser, or any other form of condenser, a vacuum pan, or any other chamber or vessel in which it is desired to produce a vacuum, as the structure of the chamber to which the pump is connected, constitutes no portion of my invention. The pump cylinder may be arranged to operate vertically, horizontally, or inclined, as will suit best the particular case to which it may be applied.

In Fig. 2, I have illustrated a vertical section through one form of my pump operatively connected to a surface condenser of the tube type. The pump includes a vertically-disposed cylinder 10, having a piston 11 and a piston rod extending downwardly therefrom and through a packing box 12 in the lower wall of a chamber or passageway 13, which receives the lower open end of the cylinder 10. The passageway 13 is of a width substantially equal to the width of the cylinder and is provided with a circular opening in its upper wall into which the cylinder extends. The cylinder may, if desired, be provided with an annular flange 14 resting on the wall of the chamber 13, so as to permit of the two being readily secured together and to support the cylinder. The chamber 13 terminates in an elbow 15 opening upwardly, and within the chamber and adjacent its connection with said elbow, I provide a suitable valve for permitting the flow of liquid through the chamber toward the cylinder, but preventing its return. Any suitable form of check valve may be employed, but I preferably provide a perforated valve seat 16, extending diagonally, and having a flexible flap 17 secured in place at the upper edge and adapted to engage with the valve seat to close the openings therein. A suitable baffle 18 may be provided for limiting the outward movement of the flap 17. The chamber 13 supports on its upper surface, a chamber 19, into which the liquid is delivered upon the down stroke of the piston. The two chambers communicate by a port 20, having a suitable check valve for permitting the upward flow of the liquid, but preventing its downward flow. The specific form of valve 105 illustrated is very similar to the valve past which the liquid flows to the chamber 13, and includes a perforated valve seat 21, a flexible flap valve 22, and a guard 23 limiting the upward movement of the edges of the valve.

At the upper end of the cylinder 10, I pro-

vide a chamber or passageway 24, leading from the cylinder substantially parallel to the passageway 13, and having an inlet valve and an outlet valve. The inlet valve 25 is preferably rotary in form, while the outlet valve is formed substantially identical with the outlet valve from the passageway 13, that is, it includes a perforated valve seat 26, a flexible flap valve 27, and a guard or baffle 28. Above the outlet valve, there is provided a chamber 29 which communicates with the chamber 19 by a vertical conduit 30, and from this conduit, adjacent its connections with the chamber 19, there is provided a main discharge conduit 31. The chamber 29 may also be provided with an air escape conduit 32 leading from the top thereof and serving to prevent the accumulation of air within said chamber. Leading to the inlet valve 25, there is provided a passage or conduit 33, and both this conduit and the elbow 15 are connected to the chamber in which it is desired to produce the vacuum. In Fig. 2, this chamber is illustrated as a condenser having a tube sheet 34 through which the steam tubes 35 extend, and having a passageway or compartment 36 communicating with the interior of all of said tubes, and communicating at its upper end with the passage 33 and at its lower end with the passage 13 through the elbow 15. The passage 13 is connected by a suitable conduit 37 with the passage 24 or the upper end of the cylinder, whereby upon the down stroke of the piston, a portion of the liquid within the lower end of the cylinder and the passage 13, may be delivered through said conduit to the cylinder at the upper side of the piston. The conduit is provided with a suitable valve 38, whereby the flow of liquid through the conduit may be controlled and the amount of liquid transferred from one end of the cylinder to the other, limited or prevented. The conduit 37 is preferably provided with a branch conduit 39 connected thereto, whereby liquid may be delivered to the upper end of the cylinder through any suitable source independent of the delivery of liquid from the lower end of the cylinder.

In the operation of the apparatus above described, the pump piston 11 is reciprocated within the cylinder by any suitable power, and the valve 25 is either continuously or intermittently rotated. Upon the up stroke of the piston, the valve 25 is closed and the larger portion of the liquids or gases above the piston is expelled past the valve 27. As the gases are above the liquids, the former escape before the latter, and I so regulate the device that all of the gas and a portion of the liquid will be expelled, so that as the piston starts on its down stroke, there will be no gas whatever in the cylinder or piston 24 below the valve 27. On the up stroke, the valve 22 remains closed, and the valve 17

opens to draw into the passage 13, liquid from the lower portion of the condenser. Upon the down stroke of the piston, the valves 27 and 17 close automatically, and the valve 25 is positively opened mechanically through the instrumentality of any suitable mechanism connected to a valve stem 25^a of the valve. The major portion of the liquid in the passage 13 is expelled past the valve 22, although a portion of the liquid is expelled through the conduit 37 and delivered to the upper surface of the piston. This liquid serves to replace any which may have leaked past the piston or has evaporated, and insures the supply of sufficient liquid above the piston to completely fill the space below the valve 22, when the piston makes the next up stroke. As there is no air whatever in the passage 24 and the upper portion of the piston when the latter starts on its down stroke and when the valve 25 is opened, air or gas will be drawn from the condenser, if there be any air or gas therein, and an extremely high vacuum may thus be obtained. In case sufficient liquid is not delivered through the conduit 37 to accomplish the results desired, additional liquid may be admitted through the conduit 39 to supply the deficiency.

The liquid in the upper end of the cylinder not only serves to fully and completely expel the air therefrom upon the up stroke, but also serves to seal the piston and prevent the escape of gas past the same. The liquid in the passage 13 serves to effectively seal the piston rod and prevent the entrance of air through the stuffing box while the piston is on its up stroke.

The details of construction illustrated in Figs. 2 and 3 do not constitute the essential features of my invention, and may be varied widely without departing from the spirit of my invention. I have shown the chamber 24 integral with a ring or cylinder section 40, intermediate the cylinder 10 and the cylinder head 41, and have illustrated the cylinder head provided with a baffle plate 42 in front of the entrance opening from the conduit 37. This construction permits of a ready separation of the parts for purposes of inspection or repair, and the baffle serves to deflect downwardly the water from the conduit 37 into the cylinder.

As previously stated, the pump may be operated in any suitable manner, and it may be employed for creating a vacuum in any suitable chamber. In Fig. 1, I have illustrated a modified form of pump, connected to the condenser 43 of a steam turbine 44. The pump is provided with a horizontally-disposed cylinder 10^a, having the piston rod of the piston 11^a secured by a cross-head 45 to a connecting rod 46. The connecting rod is pivoted to a bell crank lever 47, and the opposite end of said lever is connected by a link 130

48 to a worm wheel 49. The worm wheel intermeshes with a worm 50, which is usually provided on the turbine shaft 51 for operating the automatic governor, said governor 5 having a worm wheel 52, engaging with the worm 50 upon the opposite side thereof from the worm wheel 49. By connecting the pump to a turbine in this manner, the turbine shaft even though rotated at an extremely 10 high rate of speed, is utilized for driving the reciprocating pump at a comparatively low speed, and without the necessity for additional gear wheels on said shaft. In the specific pump illustrated in this figure, the 15 end of a cylinder corresponding to the upper end of the cylinder shown in Fig. 2, communicates with a vertical passage 24^a, having a rotary inlet valve 25^a and an automatically-operating outlet valve 27^a. This valve permits the delivery of the air or other gases to a 20 chamber 29^a, from which they may escape through a conduit 30^a to the main delivery conduit 31^a. The condenser 43 is connected to the rotary inlet valve 25 by a passage 33^a. The end of a cylinder corresponding to the 25 lower end of the form shown in Fig. 2, communicates with a vertical passage 13^a, the lower end of which communicates with a passage 15^a leading to the lower end of the condenser. At the upper end of the passage 13^a, there is 30 an automatically-operating check valve 22^a, permitting the flow of liquid into a chamber 19^a, from which leads the main outlet conduit 31^a.

35 Having thus described my invention, I claim as new and desire to secure by Letters Patent:

1. In combination, a condenser and a pump for creating a vacuum therein, one end 40 of said pump being connected to the lower portion of said condenser and having an inlet and an outlet valve and serving to withdraw water from said condenser, and the opposite end of said pump being connected to the upper 45 end of said condenser and having an inlet valve and an outlet valve and serving to withdraw air from the upper portion of the condenser, and a by-pass connecting the opposite ends of the pump, whereby upon the 50 air suction stroke of the pump, a portion of the water in the water end of the pump is transferred to the air end of the pump to insure the complete expulsion of the air upon the return stroke.

55 2. In combination, a vacuum chamber, a

double-acting pump, one end of said pump serving to withdraw liquid from the lower end of said chamber, the other end of said pump adapted to withdraw air from the upper end of said chamber, and means for transferring a portion of the liquid withdrawn from the lower end of the chamber to the opposite end of the pump.

3. In combination, a double-acting pump, including a cylinder, a piston, separate passages communicating with the opposite ends of said cylinder, inlet and outlet valves in said passages, and a by-pass connecting the opposite ends of said cylinder and serving for the delivery of liquid from one end thereof to 70 the opposite end thereof by the action of said piston.

4. An air pump, including a cylinder, a piston mounted therein, a passage communicating with said cylinder, a mechanically-operated inlet valve controlling said passage, an automatically-operating check valve controlling the outlet from said passage, and at a higher elevation than said mechanically-operated valve and means for delivering 80 liquid to said cylinder to completely fill said cylinder and passage to said valves, and to completely expel the air or gas upon the delivery stroke of the piston.

5. In combination, a condenser and a 85 pump for creating a vacuum therein, said pump including a cylinder, a piston and a piston rod, one end of said cylinder being connected to the lower end of the condenser and having an inlet and an outlet valve serving 90 to withdraw water from the condenser, and the opposite end of said pump being connected to the upper end of the condenser and having an inlet and an outlet valve serving to withdraw air from the upper portion of the 95 condenser, the piston rod extending from the cylinder at the first mentioned end thereof whereby the water seals the piston rod, and means for introducing water into the second-mentioned end of the pump to insure the 100 complete expulsion of air upon the air discharge stroke.

In testimony whereof I have signed my name to this specification in the presence of two subscribing witnesses.

CHARLES A. HAGUE.
